UNITED STATES PATENT OFFICE

162,433

GRINDING MACHINE WORK SUPPORT

Carl E. Nomann, Santa Ana, and George R. Palm,
Montebello, Calif.

Application August 4, 1950, Serial No. 11,598

Term of patent 14 years

(Cl. D37—1)

To all whom it may concern:

Be it known that we, Carl E. Nomann, a citizen of the United States residing at Santa Ana, in the county of Orange and State of California, and George R. Palm, a citizen of the United States, residing at Montebello, in the county of Los Angeles and State of California, have invented a new, original, and ornamental Design for Grinding Machine Work Support, of which the following is a specification, reference being had to the accompanying drawing, forming part thereof.

Figure 1 is a perspective view revealing the front, top, and one end of a grinding machine work support, showing our new design.

Figure 2 is a top plan view of the article illustrated in Fig. 1.

Figure 3 is an end elevation.

Figure 4 is a rear elevation.

Figure 5 is an end elevation viewed from the end opposite that revealed in Fig. 3.

Figure 6 is a front elevation.

We claim:

The ornamental design for a grinding machine work support, substantially as shown.

CARL E. NOMANN.
GEORGE R. PALM.
